TABORET

Theodore Matyas, Elmhurst, N.Y.

Application April 15, 1958, Serial No. 50,474

Term of patent 7 years

(Cl. D33—6)

FIG. 1

The back and side of the taboret not shown are plain and unornamented.

I claim:

The ornamental design for a taboret, as shown and described.
